UNITED STATES PATENT OFFICE.

GEORGE G. M. HARDINGHAM, OF LONDON, ENGLAND.

DRIVING MECHANISM FOR CYCLES.

SPECIFICATION forming part of Letters Patent No. 616,534, dated December 27, 1898.

Application filed May 24, 1897. Serial No. 637,933. (No model.)

To all whom it may concern:

Be it known that I, GEORGE GATTON MEL-HUISH HARDINGHAM, a subject of the Queen of Great Britain and Ireland, residing at 191 5 Fleet street, London, in the county of Middlesex, England, have invented new and useful Driving Mechanism for Cycles, (in respect whereof I have obtained Letters Patent in Great Britain, dated March 13, 1897, No. 10 6,683,) of which the following is a specification.

This invention relates to driving mechanism of the type in which a pedal-lever is employed in place of the usual chain-gear to 15 transmit motion from the foot to the propelling-wheel of a cycle.

The application of my invention to a rear-driven bicycle is illustrated in the accompanying drawings, whereof—

20 Figure 1 is a side elevation of the complete machine; Fig. 2, a horizontal section through the hub of the driving-wheel, showing the driving mechanism; Fig. 3, a vertical section showing portions of the driving-gear, as also 25 one of the pedal-levers in elevation; and Fig. 4, a similar vertical section, certain parts being, however, removed, so as to expose the intermediate wheel-carrier.

A pair of levers A A' carry at their forward 30 extremities pedals a a' and are connected at their after extremities to crank-pins B B', located on opposite sides of the rear wheel, the said crank-pins being arranged radially opposite to one another and keyed to the shaft C. 35 Each of the pedal-levers A A' is suspended from the frame by means of a link D, attached at a point intermediate of its length, the link thus affording the lever a floating fulcrum. It will, however, be obvious that the lever 40 may be mounted in a fixed guide or bearing, the employment of a floating fulcrum being in no way essential. Between the crank-shaft C and the hub E of the road-wheel is arranged a three-part differential gear, comprising a central pinion F, a surrounding internally-toothed wheel G, and an intermediate toothed wheel H or series of such wheels, the latter meshing with the central pinion F and with the internally-toothed wheel G. The crank-

shaft C is secured by means of the sleeve g 50 and key c to the internally-toothed wheel G. The central pinion is connected by means of the sleeve f to the hub E of the road-wheel, while the studs h, on which the intermediate toothed wheels H are mounted, are carried in 55 a disk h', which is secured by means of the sleeve h² and feather h³ to the frame K of the machine. Under these circumstances the direction of rotation of the road-wheel relatively to that of the crank-shaft is reversed, 60 while the speed of rotation is increased in such degree as may be desired by suitably proportioning the diameter of the central pinion F to that of the surrounding toothed wheel G. The studs h are preferably sup- 65 ported at their outer extremities in a ring h⁴, which is secured to the disk or carrier h' by means of studs h⁵. The chamber which 70 encloses the gear and forms the hub of the road-wheel may be partially charged with lubricating fluid, the toothed gear thus running in an oil-bath, the lubricant being introduced or discharged by way of the screw-plugged orifice e.

What I claim as my invention, and desire 75 to secure by Letters Patent, is—

The herein-described driving mechanism for rear-driven cycles, comprising a pair of vibrating and reciprocating pedal-levers of the first order, a crank mounted centrally in 80 the road driving-wheel and carrying at its opposite extremities cranks respectively connected direct to the pedal-levers, and, concentric with the crank-shaft, a three-part differ- 85 ential gear whereof the outer wheel is connected with the shaft, the central pinion with the road-wheel, and the intermediate-wheel carrier with the frame, the intermediate 90 wheels meshing both with the outer wheels and with the central pinion, substantially as herein described and whereby the motion transmitted to the road-wheel is in the reverse direction to that imparted to the crank-shaft.

G. G. M. HARDINGHAM.
